UNITED STATES PATENT OFFICE.

DANIEL M. ROTHENBERGER, OF READING, PENNSYLVANIA, ASSIGNOR OF ONE-THIRD
TO FRANCIS F. SEIDEL, OF READING, PENNSYLVANIA.

MAUSOLEUM.

1,153,956.

Specification of Letters Patent. Patented Sept. 21, 1915.

Application filed September 18, 1914. Serial No. 862,277.

To all whom it may concern:

Be it known that I, DANIEL M. ROTHENBERGER, a citizen of the United States, residing at Reading, in the county of Berks 5 and State of Pennsylvania, have invented certain new and useful Improvements in Mausoleums, of which the following is a specification.

My invention relates to mausoleums, and 10 my general object is to provide an improved multiple-crypt structure which will combine with provision for convenient and satisfactory operation and maintenance and for suitable emotional effects, a complete 15 sanitary arrangement; the latter involving provision for independently ventilating and draining each separate crypt, as well as for cutting off from all of them such exterior or 20 interior communication as might cause harmful effects either to the entombed bodies or to those who attend at interments.

The several features of the invention are 25 fully described in connection with the accompanying drawings and are specifically pointed out in the claims.

Figure 1 is a partly sectional plan view 30 of a complete mausoleum embodying my invention in preferred form. Fig. 2 is an enlarged cross-sectional view of the same on the line 2—2 of Fig. 1. Fig. 3 is a partial side elevation, partly in section on the line 3—3 of Fig. 2. Fig. 4 is an enlarged fragmentary sectional view similar to Fig. 2 showing detail construction of the crypts. 35 Fig. 5 is a rear view, in direction of arrow 5, Fig. 4. Fig. 6 is a horizontal section, on the line 6—6 of Fig. 5. Fig. 7 shows a slightly modified arrangement of the sealing receptacles.

The preferred form of complete structure 40 which is indicated in the drawings as embodying my invention, comprises an arrangement of individual crypts 10 in two parallel series of tiers, $a a a a$ and $a^1 a^1 a^1 a^1$, which are separated by a vertical ventilation space 11 formed between the adjacent rear crypt walls 12, 12; a foundation 13, of concrete or the like, upon which said tiers 45 of crypts are erected, with a ventilation space 15 under the latter having communication with the atmosphere through grated and screened lateral openings 16, 16^a; and a roof 18 forming a ventilation space 19 50 above the crypts which is provided with similarly grated and screened lateral open-

ings 20, 20^a, and which serves in connection with the lower space 15 and the vertical space 11 to insure a circulation of air around the tiered crypts. The roof 18, as shown, extends beyond the front walls of the crypts, 60 and is carried upon series of columns 25, so as to form covered porticos 26, 26 along the crypt fronts. In order that the front of each crypt of the structure may be freely exposed to the atmosphere and yet be made 65 conveniently accessible from a common reception point, as well as to produce a suitable esthetic effect, I preferably arrange this porticoed crypt structure in bent or curved form around an inner open area 30 (Fig. 1) 70 upon which the tiers of crypts $a^1 a^1 a^1 a^1$ front, and to which access is provided between the continuous ends of the crypt structure; said open area, as indicated, having erected thereon a separate chapel structure, 31, whereby proper and convenient utilization of the crypt structure is provided 75 for.

The several tiers of each parallel series of crypts $a a a a$ or $a^1 a^1 a^1 a^1$ are built up from 80 the impervious concrete foundation 13, upon partition walls 35, 35, 35 rising between adjacent vertical series of crypts 10, with the rear crypt wall 12, the bottom crypt floor 36 above the air space 15, the top crypt 85 cover 37 below the roof covered air space 19, and the intermediate series of crypt floors 38, 38, 38, 38, formed as an integral structure of concrete or other impervious material. Each crypt floor is slightly inclined downward from the front wall 39 90 toward the rear wall 12 of the crypts; which fronts are separately closed and sealed when interments are made, as hereinafter specifically described.

The atmospheric openings 16 and 16^a to the lower ventilation space 15, and 20 and 20^a to the upper ventilation space 19, are covered by fine screens 40 and gratings 41 adapted to exclude animal life or harmful 100 material while permitting requisite circulation of air through said spaces and the communicating vertical ventilation space 11 at the rear of the crypts; and chemical receptacles 42 or like traps are provided adjacent 105 each of said openings to further safeguard the same.

An essential requirement to the securing 110 of satisfactory sanitary conditions involves the provision also of effective means for

thoroughly ventilating and draining each of the crypts independently, for avoiding all communication between the crypts whether occupied or not so as to effectively prevent contamination of the dead or the living either by the spread of disease germs from the interred bodies or the introduction of harmful exterior life or matter in any form. To accomplish this I provide in connection with a general exterior ventilation system such as already described, a series of vertical conduits 50, 50, 50, 50, 50 for each vertical series of crypts: Said conduits being preferably provided in the rear wall structure 12 as indicated, and extending vertically with the upper end of each in communication with the upper ventilation space 19, and the lower end thereof in communication with the lower ventilation space 15 either directly or through the connecting rear-wall space 11; and each conduit being provided intermediate of its length with separate lateral openings 52 and 53 communicating respectively with the upper and lower portions of a particular crypt. The special conduit thus provided for each single crypt, serves the latter exclusively as both a ventilating and draining means; the upper opening 52 serving as an outlet for ventilating the same, while the lower one 53 discharges any seepage occurring therein.

To provide for proper disinfection of the discharging gases and seepage, and also for sealing the conduits so as to exclude anything foreign, each of them is arranged to terminate respectively in an upper receptacle 54 and a lower receptacle 55; both of which receptacles are adapted to receive a suitable material, such as chlorid of lime, adapted to serve both as a disinfectant of the discharging gases and seepage and as a sealing medium. These receptacles are preferably located at the top and bottom portions respectively of the crypt structure as particularly shown, but may be otherwise arranged, as indicated for instance in Fig. 7 where separate lower receptacles 55^a are provided for the several conduits at different heights in the connecting rear ventilation space 11.

The closure of the front of each crypt, after interment therein, is effected by means of separate slabs 60 and 61 as indicated; the inner one 60 of these being a sealing slab suitably secured so as to hermetically close the crypt; and the spaced outer one 61 being an inscription slab. In order to avoid the repellent effect of utter darkness in the crypt, I provide for securing a subdued indirect light therein by suitably forming both the inner and outer slabs with light-admitting portions, 62 and 63 respectively, and so arranging the slabs relatively that the

light-admitting portion of the inner one is covered by the inscription-plate portion of the spaced outer one. To provide further protection I also preferably provide an ornamental grating 64 in front of the inscription slab.

The chapel structure 31 provided in the central area 30 is entirely separate from the inclosing crypt structure, the adjacent ends 29 of which latter are spread so as to provide access to the chapel, the open space surrounding it, and the inner crypt corridor, so that attendants at interments are at all times free from inclosure in the crypt structure; and the open crypt in which an interment is about to be made is absolutely free from communication with any of the closed crypts. The grouping of crypts is at all times thoroughly ventilated and perfectly protected from exterior harm; and each crypt is similarly protected, and at the same time independently ventilated and drained and effectively cut off from communication with other crypts.

What I claim is:

1. A mausoleum having crypts arranged in tiers and provided with exterior ventilating spaces above, below, and in the rear of the tiers; the rear wall of the tiers having independent conduits one for each crypt, each crypt having a sloping floor and a drain opening in the plane thereof leading into its respective conduit and a ventilating opening in the upper portion of its rear wall also leading into the same conduit, means at the lower end and means at the upper end of said conduits to contain disinfectant, said means being open to the surrounding spaces.

2. In a mausoleum, a foundation, a roofed structure, crypt tiers between and spaced from the foundation and roof to provide ventilating spaces communicating with the outer atmosphere, said crypt tiers being in parallel series with a ventilating passageway between their rear walls, disinfectant containing receptacles open at their upper ends and arranged on the rear walls of said tiers and within the intermediate ventilating passageway, disinfectant containing receptacles adjacent the upper walls of said tiers, the rear walls of said tiers having independent ventilating and draining conduits one for each tier, and said conduits opening into the bottom portions of said receptacles.

In testimony whereof I affix my signature in presence of two witnesses.

DANIEL M. ROTHENBERGER.
